CLAIM

The ornamental design for a bracelet as shown and described.

DESCRIPTION

FIG. 1 is a front, right and top perspective view of a bracelet showing my new design;

FIG. 2 is a rear, left and bottom perspective view thereof;

FIG. 3 is a top view thereof;

FIG. 4 is a bottom view thereof;

FIG. 5 is a right view thereof;

FIG. 6 is a left view thereof;

FIG. 7 is a front view thereof;

FIG. 8 is a rear view thereof; and,

FIG. 9 is an enlarged view of a portion labeled as "9" on FIG. 1.

The long dash-short dash broken lines depict enlargement boundaries that form no part of the claim.

1 Claim, 9 Drawing Sheets
